E. L. VAN PELT

FILM MENDING AND ASSEMBLING MACHINE

Filed July 6, 1920

Inventor
E.L. VAN PELT

334 *Lynn L. Steele* Attorney

UNITED STATES PATENT OFFICE.

ELMER L. VAN PELT, OF DENVER, COLORADO, ASSIGNOR TO GEORGE FRUTH, OF DENVER, COLORADO, AND HENRY E. MC ELWAIN, OF HOLYOKE, MASSACHUSETTS.

FILM MENDING AND ASSEMBLING MACHINE.

Application filed July 6, 1920. Serial No. 394,138.

To all whom it may concern:

Be it known that I, ELMER L. VAN PELT, a citizen of the United States, residing at the city and county of Denver and State of Colorado, have invented certain new and useful Improvements in Film Mending and Assembling Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide a machine for use in mending and assembling motion picture films, by means of which the overlapping film ends may be cemented and pressed or clamped together to form a firm bond.

Briefly the invention comprises a frame having a base and an overhanging arm spaced therefrom to provide a space in which one of a pair of cutting blocks is mounted stationarily and in which the other of the pair of cutting blocks reciprocates along the side of the fixed block. Each block has a pair of slots to receive two film ends in overlapping relation. One slot in each block receives that portion of one film end which is to be trimmed off during the operation, while the other slot receives the body of the other film end. The frame also carries a cement receptacle from which a wick leads which is adapted to be reciprocated into position between the opposed film ends and the corresponding pressing or clamping faces of the cutting blocks. The wick is withdrawn leaving the opposed film surfaces with a coat of cement. The movable block is then reciprocated whereby the extremities of the films are cut off, thus giving a neat finish, and the opposed cemented film surfaces are pressed together until a firm bond is formed.

In the drawings

Fig. 1 is a side elevation of the device taken from line 1—1 of Fig. 3.
50 Fig. 2 is an end elevation from line 2—2 of Fig. 1.

Fig. 3 is a view partially in plan and

partially in section as indicated by line 3—3 of Fig. 1.

Fig. 4 is a side elevation of the cutting blocks removed from the frame but in assembled relation to each other.

Fig. 5 is a section on line 5—5 of Fig. 4.

The frame 10 comprises a base 12 having perforated ears 14 for the reception of screws 15 to secure the device to a support, and an overhanging arm 16 spaced from the base 12. The intermediate portion 18 of the frame is provided with a cement receiving cavity 20 which is filled thru an aperture in the top of the frame adapted to be closed by a plug 22.

The frame 10 has a vertically extending transverse wall 24 at the rear end of the space between the base 12 and arm 16, 70 against which the inner or rear ends of the two cutting blocks 25 and 35 abut. The height of the stationary cutting block 25 is equal to the height of the space between base 12 and arm 16, so that said block 25 fits 75 snugly between said base and arm. The block 25 comprises an upper jaw 26 and a lower jaw 28, the jaw 28 having a transversely offset ledge whose upper face 30 constitutes a clamping seat or bench against 80 which the film is to be pressed. The block 25 is slotted to produce a beveled face 32 on jaw 26 and a beveled face 33 on jaw 28. These slots extend rearward from the front end of the block a distance a little greater 85 than the width of film to be handled, and produce between them a forwardly projecting tongue 34 whose upper face inclines downward slightly as indicated at 134 to form an efficient cutting edge; see dotted 90 lines in Fig. 4.

Similarly, the movable block 35 has an upper jaw 36 and a lower jaw 38, the upper jaw having a laterally offset overhanging ledge 39 which presents a clamping face or 95 bench 40 opposed to bench 30. This block is slotted as is block 25 to produce beveled faces 42 and 43 like those at 32 and 33, and to produce a forwardly projecting tongue 44 like tongue 34 except that its lower face 144 100 (Fig. 4) inclines upward. The rear portion of ledge 39 is cut away to form a vertical shoulder 45 to accommodate a wick receiving tube 46 mounted in wall 24 as

2
indicated at 48 and communicating with cavity 20.

The length of blocks 25 and 35 is preferably about equal to that of arm 16, while 5 tongues 34 and 44 project slightly forward as shown. The lower jaw 38 is not so deep as jaw 28 in order that block 35 may be reciprocated vertically alongside block 25. Block 25 is retained in position against block 10 35 by means of a pair of leaf springs 50 which are secured at 52 to the frame 10 and whose forward ends are offset to form detents 54 to engage in recesses or kerfs vertically disposed in the sides of jaws 26 and 15 28.

Block 35 is supported by means of a pin 55 which is threaded into its upper portion and which is reciprocably mounted in arm 16. The head of pin 55 is flanged as indicated at 56 and bears against a lower cam face 58 on the lower end of a handle 60 which is eccentrically pivoted between ears on arm 16 as indicated at 62. Nose 64 on the extreme tip of handle 60 engages a 20 shoulder 65 on arm 16 to limit swinging movement of said handle. A spring 66 is mounted on pin 55 with its upper end in engagement with flange 56 and its lower end resting in seat 68 in arm 16. This spring 25 30 normally retains block 35 and handle 60 in elevated position. In order to firmly retain the parts in operative relation and eliminate any tendency of block 35 to rotate on axis of pin 55 a pair of bent leaf springs 35 40 70 are secured to the side of the frame at 72 and have their tips 74 bent parallel to the side walls of block 35 to engage the upper and lower jaws 36 and 38. Thus the snug fit of block 25, the springs 50 and 70, and pin 55, maintain the operative positions of the parts.

For properly positioning the film ends F, a plate 75 is secured to the base 12 and is provided with upstanding webs 76 whose 45 upper edges form supports for the film ends, the corners of said upper edges being provided with teeth or projections 78 to engage in the sprocket holes O. These teeth 78 are higher on one side than on the other an 50 amount approximating the thickness of the tongues 34 and 44, due to the fact that one film end lies upon the tongues while the other end lies under them on bench 30, as indicated at b and a respectively.

55 For cementing the overlapping ends of the films, a wick 80, which has preferably a stiff core, is provided, the wick being adapted to take up cement and conduct it to its forward extremity by capillary attraction. The forward end of said wick lies normally in the forward end of the tube 46 so as to be close to said rear wall 45 of block 35. At the rear of the transverse portion of wick 80, a stem 82 is connected 60 65 which is provided with an operating knob

84. The stem 82 is reciprocable in a horizontal slot which is normally covered by a horizontal plate 85 reciprocable with stem 82 and knob 84, the plate 85 preventing evaporation of the cement. 70

In operation, the block 35 is initially in its normal position as shown in the drawings. One piece of film F is brought from the right and placed under tongues 34 and 44 so that it lies on bench 30 and the extremity a to be trimmed off lies to the left. Another piece of film F is brought from the left and laid on tongues 34 and 44 and beneath bench 40, so that the extremity b to be trimmed off lies at the right. Knob 84 is then grasped 80 and wick 80 projected into the space between the two films and between tongues 34 and 44 to coat the opposed film portions with cement. The wick is then withdrawn, and handle 60 depressed in the direction of 85 the arrow, Fig. 1. The adjacent edges of bench 40 and tongue 34 cooperate to sever extremity b, while the adjacent edges of bench 30 and tongue 44 cooperate to sever extremity a. The cemented faces of the 90 opposing films are then pressed and clamped together between benches 30 and 40 and held in such position for a few seconds to obtain a firm union. The handle 60 is then released, whereupon spring 66 returns block 95 35. The film is then removed, the extremities a and b falling away.

It will be noted that the end of the tube 46 which normally houses the end of the cement laden wick 80, terminates close to 100 the edge of the film ends F when in position. It will also be noted that the tongues 34 and 44 are farther apart than are the adjacent film surfaces when in position. Thus when the wick is reciprocated by knob 105 84, the cement is wiped on the film surfaces only, leaving the dies or blocks 25 and 35 clean. In this manner gumming of the blocks or any other part of the machine is entirely avoided and a neat, clean joint is 110 produced in the film.

I claim:

1. A film mending and assembling machine comprising a pair of relatively movable cutting blocks each of which has a 115 pair of relatively fixed cutting edges.

2. A film mending and assembling machine comprising a pair of relatively movable cutting blocks each of which has a pair of film receiving slots. 120

3. A film mending and assembling machine comprising a pair of relatively movable cutting blocks each of which has a pair of film receiving slots and a pair of cutting edges. 125

4. A film mending and assembling machine comprising a pair of relatively movable cutting blocks each of which has a pressing bench and a pair of film receiving slots. 130

5. A film mending and assembling ma

- chine comprising a pair of relatively movable cutting blocks each of which has a pressing bench, a pair of film receiving slots, and a pair of cutting edges.
- 5 6. A film mending and assembling machine comprising a pair of relatively movable cutting blocks, each of which has an offset ledge to provide a pressing bench, said pressing benches opposing each other, each 10 block having a tongue separated from the body of the block by a film receiving slot.
7. A film mending and assembling machine comprising a pair of relatively movable cutting blocks, each of which has an offset ledge to provide a pressing bench, said pressing benches opposing each other, each block be provided with a tongue separated from the body of the block by a film receiving slot, each tongue having a 15 cutting edge, and each block body having a cutting edge.
8. A film mending and assembling machine comprising a pair of relatively movable cutting blocks each of which has a pair 20 of cutting edges and each of which has a pressing bench, and means for cementing opposed film surfaces lying adjacent said benches.
9. A film mending and assembling machine comprising a pair of relatively movable cutting blocks, each block having a pressing bench, said benches opposing each other, a tongue member on each block separated from the body of the block by 25 a slot, both the body of each block and each tongue having a cutting edge, and means located adjacent said blocks for applying cement to opposed film faces lying adjacent said benches.
- 40 10. A film mending and assembling machine comprising a pair of relatively movable cutting blocks, each block having an upper jaw and a lower jaw, and a tongue between the jaws and spaced therefrom by film receiving slots, the upper jaw of one block and the lower jaw of the other block having offset overhanging ledges whereby the ledges present opposed pressing benches, the ledge and the tongue of each block having cutting edges cooperating respectively 45 with the edges on the other block.
11. A film mending and assembling machine comprising a pair of relatively movable cutting blocks, each block having upper and lower jaws and a tongue between the jaws and spaced therefrom by slots, each block having a ledge offset toward the other block presenting opposed pressing benches, each block having two cutting 55 edges cooperating with the cutting edges on the other block, and a reciprocable cement applying member movable between opposed film faces on said benches to coat said faces with cement.
- 60 12. A film machine comprising a pair of 65 relatively movable cutting blocks, and means to apply cement between said blocks.
13. A film joining machine comprising a pair of blocks adapted to receive overlapped film-ends between them, and means for wiping cement on opposed film faces between 70 said blocks.
14. A film joining machine comprising a pair of relatively movable cutting blocks adapted to receive between them overlapped film ends in spaced relation, and reciprocable means movable into position between the opposed film-faces for wiping cement on said faces.
15. A film joining machine comprising a pair of relatively movable cutting blocks having offset ledges providing opposed pressing faces adapted to receive overlapped film-ends between them in spaced relation, each block having a tongue 85 separated from the body portion thereof by a film-receiving slot, said tongues spacing the film ends, and cement applying means movable into position between the opposed film faces and between said tongues 90 for wiping cement on said film faces.
16. A film joining machine comprising a frame, a stationary cutting block mounted in said frame, a movable cutting block reciprocable alongside the fixed block, a tongue on each block separated from the body of the block by a film receiving slot, said tongues being spaced from one another in one direction and adapted to space film-ends in another direction, a cement receptacle connected with said frame, and means leading from said receptacle and adapted to be projected between said tongues and between said film-ends to wipe cement 95 on the opposed film faces.
17. A film mending and assembling machine comprising a pair of relatively movable cutting blocks, each of which has a tongue separated from the body of the block by a film-receiving slot.
18. A film mending and assembling machine comprising a pair of relatively movable cutting blocks, each of which has a tongue separated from the body of the block by a pair of film-receiving slots, each block 100 having a pair of cutting edges.
19. A film mending and assembling machine comprising a pair of relatively movable cutting blocks having opposed pressing benches, and a reciprocable member for 120 applying cement to opposed film faces lying between said benches.
20. A film mending and assembling machine comprising a pair of relatively movable cutting blocks, a frame in which said blocks are mounted, a cement reservoir connected with said frame, a cement applicer extending from the reservoir and reciprocable between said blocks, and means connected with said applicer and extending 125 130

through said frame for manipulation of the applier.

21. A film handling machine comprising a frame, a movable block mounted in said frame and adapted to engage a film, a reciprocating stem mounted in said frame and having one end fixed in said block, a spring secured to the frame and pressing against

the block, a relatively fixed block also mounted in the frame, and a spring secured to the frame and pressing against said fixed block to press the latter against the movable block.

In testimony whereof I affix my signature.

ELMER L. VAN PEELT.
